UNITED STATES PATENT OFFICE.

WILLIAM H. JOHNSON, OF LEHIGHTON, PENNSYLVANIA.

RAIL-BED PLOW.

Application filed January 6, 1923. Serial No. 611,072.

To all whom it may concern:

Be it known that I, WILLIAM H. JOHNSON, a citizen of the United States, residing at Lehighton, in the county of Carbon and 5 State of Pennsylvania, have invented certain new and useful Improvements in Rail-Bed Plows; and I do hereby declare the following to be a full, clear, and exact description of the invention, such as will enable others 10 skilled in the art to which it appertains to make and use the same.

The invention relates to a plow designed more particularly for the bed of railroads, whereby the ballast may be loosened when 15 required to admit of leveling and proper surfacing to insure drainage and prevent washout.

Other objects and advantages will be apparent and suggest themselves as the nature 20 of the invention is understood.

While the drawings illustrate an embodiment of the invention it is to be understood that in adapting the same to meet different conditions and requirements, various changes 25 in the form, proportion and minor details of construction may be resorted to without departing from the nature of the invention.

Referring to the accompanying drawings forming a part of the application,

30 Figure 1 is a side view of a machine of the character aforesaid embodying the invention,

Figure 2 is a top plan view thereof,

35 Figure 3 is a vertical longitudinal section on the line 3—3 of Figure 2, looking in the direction of the arrows,

Figure 4 is an end view,

Figure 5 is an enlarged sectional detail on the line 5—5 of Figure 2,

40 Figure 6 is a horizontal section on the line 6—6 of Figure 5,

Figure 7 is a sectional detail on the line 7—7 of Figure 6, looking in the direction of the arrows,

45 Figure 8 is a sectional detail on the line 8—8 of Figure 1, and

Figure 9 is a sectional detail on the line 9—9 of Figure 1.

Corresponding and like parts are referred 50 to in the following description and designated in the several views of the drawings by like reference characters.

The machine embodies a bed or platform 1, which is mounted upon trucks 2 disposed 55 at opposite ends of the machine and constructed to run upon a track 3. Side wings

4 are pivotally mounted upon the lower ends of vertically disposed posts 5, said posts being stepped at their lower ends in cross-pieces 6 which are bolted or otherwise secured at their inner ends to the bed 1. A crosspiece 7 connects the upper ends of the posts 5, and braces 8 connect the upper ends of the posts 5 with the ends of the bed 1 and pass over uprights 9, which are secured at 60 their lower ends to the bed in any substantial way. Short crosspieces 10 and 11 are disposed above and below the bed 1 and the respective wings 4 and are secured at their outer ends to the rear portion of the wings 70 and their inner ends loosely embrace the bed so as to hold the wings 4 in the plane of the bed and prevent relative vertical displacement thereof. Vertical rods 12 and 13 are secured at their lower ends to opposite ends 75 of the wings 4. A longitudinally disposed plate 14 is arranged parallel with the bed 1 and is secured to the upper ends of the rods 12 and 13 and receive the upper end of the post 5. A transverse shaft 15 is mounted 80 upon the crosspiece 10 and is provided at its outer end with an arm 16 and at its inner end with a lever 17, whereby the shaft 15 may be turned. A latch 18, connected with a lever 19 pivoted to the lever 17, coacts 85 with a toothed bar 20, whereby to hold the lever 17 and shaft 15 in the required adjusted position. A contractile helical spring 21 cooperates with each of the levers 17 to hold it in a given position with the latch 19 90 in engagement with the toothed bar 20. A member 22 is pivotally mounted upon the outer end of each of the shafts 15 and its opposite end is provided with a block 23 to which is journaled a transverse shaft 24. A 95 pawl 25 and an arm 26 are secured to the shaft 24, and a link 27 connects the arm 26 with the arm 16. When the lever 17 is operated, the shaft 15 is turned and effects a corresponding turning of the shaft 24, 100 whereby the pawl 25 is thrown into or out of engagement with the teeth of a vertically disposed rack bar 28, which passes loosely through the plate 14 and the member 22. A crosshead 29 is rigidly connected to the lower 105 end of the rack bar 28, whereby both move together. A bar 30 is mounted upon the crosshead 29 to move thereon transversely of the machine. A longitudinal beam 31 is secured intermediate its ends to an end of 110 the crosshead 29 and is provided at opposite ends with standards 32 equipped at their

lower ends with plowpoints 33. A similar longitudinal beam 34 is attached intermediate its ends to the slide bar 30 which is provided at opposite ends with pivoted standards 35 supplied at their lower ends with plowpoints 36. A bar 37 secured at its lower end to the slide bar 30, extends vertically and passes loosely through the plate 14. The upper ends of the pivoted standards 32 and 35 are connected by members 38 which preferably consist of bars, and these bars 38 are connected at one end to a vertically disposed rod 40 which has its upper portion passing loosely through the plate 14.

15 A bracket 39 fast to one end of a transverse shaft 41 loosely receives the rod 40. A lever 42 secured to the shaft 41 carries a latch 43 which is connected to a lever 44 pivoted to the lever 42, the latch 43 coacting with a segment 45, whereby to hold the lever 42 and the plow standard in the required adjusted position. The pitch of the plowpoints is regulated by turning the shaft 41 and since both bars 38 are connected to 25 each other and to the rod 40 all the plowpoints of one group or gang are simultaneously adjusted.

A standard 46 rising from the bed 1 supports a transversely disposed adjusting screw 47 which has screw thread engagement with a block 48 through which the bar 37 loosely passes. Rotation of the screw 47 in one direction or the other effects lateral adjustment of the lower end of the bar 37, 35 and a corresponding movement of the slide bar 30, whereby provision is had for lateral adjustment of the plowpoints 33 and 36. Vertical adjustment of the plowpoints is effected by means of a longitudinal beam 49 40 and vertically disposed adjusting screw 50 mounted in the plate 14 and having screw thread engagement with the beam 49. Links 51 connect the beam 49 with the respective beams 31 and 34 and in this manner provision is had for lateral adjustment of said beams and the plowpoints carried thereby. The rods 12 and 13 and the posts 5 pass loosely through the beam 49 and serve to maintain the same in proper position without interfering in the least with its vertical adjustment.

In practice, the machine is mounted upon the track 3 and the group of plowpoints are disposed at opposite ends and upon opposite sides thereof and face in reverse directions, one group or gang of plows operating upon one side of the track when the machine is traveling in one direction and the other group or gang operating upon the opposite side of the track when the machine is moving in the reverse direction. The plow may be coupled to a locomotive or train as preferred and found most advantageous. From the foregoing it will be understood that the plowpoints of a group or gang may be ad-

justed laterally, vertically and pivotally according to the nature of the work.

What is claimed is:

1. A rail bed plow comprising a main frame mounted upon wheels and adapted to be propelled upon the track of a railroad, plows at opposite ends and upon opposite sides of the main frame to loosen and level the ballast upon opposite sides of the track, one set of plows being adapted to operate in one direction and the other set in the reverse direction, and means for independently adjusting certain of the plows of one set laterally with respect to the remainder of the plows of the same set to regulate the lateral extent of operation of the plows of a set.

2. A rail bed plow comprising a main frame including a bed mounted upon wheels a laterally adjustable wing, upper and lower crosspieces secured at one end to the wing and loosely embracing said bed at the opposite end, plows carried by said wing, means mounted upon the upper crosspiece for effecting adjustment of the plows, and connections between said plow adjusting means and plows.

3. In a plow of the character specified, a main frame, including a bed mounted upon wheels, a wing pivotally connected at one end with the bed, upper and lower crosspieces secured at one end to the wing and loosely embracing the bed between their opposite end, a plow carried by the wing and adjustable independently thereof, and means mounted upon said upper crosspiece and having connection with the plow to effect independent adjustment thereof.

4. In a plow of the character specified, a main frame, members carried by the main frame and having relative lateral adjustment, plows carried by each of said members, and means for effecting lateral adjustment of said members relative to each other to vary the transverse distance between the plows of the respective members.

5. In a plow of the character specified, a main frame, members carried by the main frame and adjustable vertically with respect to the frame and laterally one with respect to the other, vertically disposed bars having connection with the respective members, means cooperating with one of said bars to hold it in the required adjusted position vertically, means mounted upon the main frame and in cooperative relation with the other one of said bars to effect lateral adjustment thereof, and plows carried by the respective members.

6. In a plow of the character specified, a main frame, members carried by the main frame and adjustable vertically with respect to the frame and laterally one with respect to the other, vertically disposed bars having connection with the respective members,

- means cooperating with one of said bars to hold it in the required adjusted position vertically, means mounted upon the main frame and in cooperative relation with the 5 other one of said bars to effect lateral adjustment thereof, plows pivotally mounted upon the respective members, and means mounted upon the main frame and having connection with the plows to effect independent pivotal adjustment thereof for 10 varying the pitch.
7. In a plow of the character specified, a main frame, a wing mounted upon the main frame, means on the main frame to effect lateral adjustment of said wing, members carried by said wing and having a relative transverse adjustment, a beam, means for adjusting the beam vertically, independent connections between said vertically adjustable beam and the said respective members, plows pivotally mounted upon the respective members, and means mounted upon the main frame and having connection with the plows to effect pivotal adjustment thereof in any vertical or lateral adjusted position.
8. In a plow of the class described, a wheeled frame, a vertically disposed bar supported by said frame and adapted for 30 vertical adjustment relative to the frame, a member supported by said bar at its lower end, a second member supported by the first member and laterally adjustable relative thereto, a vertical bar adapted for vertical movement and connected at its lower end to said second member, a pair of horizontally disposed bars one of which is secured to each of said members, plows secured to said pair of bars, means for effecting lateral adjustment of said second named vertical bars to effect lateral adjustment of said second named member to vary the transverse distance between the plows, and means for elevating the vertical bar first named to 40 raise the bars.
9. In a plow of the class described, a wheeled frame, a vertical bar supported by said frame and adapted for vertical movement relative to the frame, a member supported by said bar at its lower end, a second member supported by the brace member and laterally adjustable relative thereto, a vertical bar adapted for vertical movement and connected at its lower end to said second member, a pair of horizontally disposed 50
- bars one of which is secured to each of said members, a horizontally disposed bifurcated bar disposed above said pair of bars and straddling said vertical bars, plows pivoted intermediate the ends of their standards to 60 said pair of bars and pivoted adjacent the upper ends of their standards to the bifurcated bar, means for effecting lateral adjustment of said second named vertical bar to affect lateral adjustment of said second named member relative to the first named member to vary the transverse distance between said plows, means for elevating the vertical bar first named to raise the plows, and means for moving the horizontally disposed bifurcated bar in the horizontal direction to rock the plows on their pivotal connection with the pair of horizontally disposed bars to thereby effect a change in the hitch of the plows.
10. In a plow of the class described, a wheeled frame, a pair of members carried by said frame, one of said members being laterally adjustable relative to the other of said members, a bar carried by each of the members and disposed transversely thereof, plows carried by each of said bars, and means for effecting lateral adjustment of said members to vary the transverse distance between said plows.
11. In a plow of the class described, a wheeled frame, a pair of members carried by said frame, one of said members being laterally adjustable relative to the other of said members, a bar carried by each of said members and disposed transversely thereof, a plow pivoted to the end of each of said bars and having its blade disposed below the bar and having its standard projecting above the same, a bar disposed above said first named bars and pivoted to the upper end of each of said standards, means for effecting lateral adjustment of said members to vary the transverse distance between the plows, and means for moving said last named bar to rock said bars on their pivotal connection with the first named bars to effect a change in the pitch of the plows.

In testimony whereof I affix my signature in presence of two witnesses.

WILLIAM H. JOHNSON.
